UNITED STATES PATENT OFFICE

2,596,354

DOOR SUPPORT FOR PRESSURE VESSELS

Walter H. Zollinger, Bethlehem, Pa., assignor to Bethlehem Steel Company, a corporation of Pennsylvania

Original application July 5, 1947, Serial No. 759,039. Divided and this application December 6, 1949, Serial No. 131,448

14 Claims. (Cl. 18—7)

1

This invention relates broadly to large sized pressure vessels used in vulcanizing plastic materials which are subjected to very high pressures and more especially to a quick acting door closure therefor which will allow quick access to the contents of the vessel immediately upon the release of the pressure in the vessel, and is a division of my copending application Serial No. 759,039, filed July 5, 1947, for Pressure Vessel.

A further object of the invention relates to the means for opening and closing the door and the manner of locking the door in its closed position.

Another object of the invention relates to a safety device for the vessel. Should the operator by mistake try to admit pressure to the vessel when it is not in the full locked position the interlocking valve will bypass the same and prevent pressure from building up in the vessel.

A further object of my invention is to provide an auxiliary support for large and heavy doors during the opening and closing operations.

Other objects of my invention will appear hereinafter.

Having thus given a general description of the objects of my invention I will now in order to make the same more clear, refer to the annexed three sheets of drawings forming a part of this specification and in which like characters of reference indicate like parts.

Figure 1 is a side elevation of a pressure vessel embodying my invention, with a portion of the vessel shown in section.

Fig. 2 is a front end elevation.

Fig. 3 is a horizontal section through the interlocking valve casing at the closure end of the pressure vessel taken on the line 3—3 of Fig. 2.

Fig. 4 is a horizontal longitudinal section through the closure end of the pressure vessel taken on the line 4—4 of Fig. 2, but showing the door in the open position in full lines and in the closed position in dotted lines.

Fig. 5 is a horizontal longitudinal section through the closure end of the pressure vessel taken on the same line 4—4 of Fig. 2 showing the door in the closed position and locked.

Fig. 6 is a bottom side elevation of the closure end of the pressure vessel.

Fig. 7 is a transverse section through the interlocking valve casing taken on the line 7—7 of Fig. 3.

Fig. 8 is a transverse section through the interlocking valve casing taken on the line 8—8 of Fig. 6.

Fig. 9 is a top plan view of the closure end of the pressure vessel.

2

Fig. 10 is an enlarged vertical section of the jib-crane and adjacent parts showing the manner of mounting the same taken on the line 10—10 of Fig. 1, and

Fig. 11 is a diagrammatic view showing the pipe connections to the pressure vessel and the valves for controlling the flow of fluid pressure to and from the same.

Referring now to the various characters of reference on the drawings, the numeral 1 indicates the pressure vessel of tubular shape having one end closed as at 2, provided with threaded openings 3, 4 and 5 for receiving pipe connections for the fluid pressure to and from the vessel. The other end of the tubular pressure vessel is open and provided on its inner surface with a tapered door jamb surface 6 for receiving the tapered seating surface 7 of a door 8 having an annular groove 9 for receiving a gasket 10 to prevent the fluid from escaping from the vessel. The end of the pressure vessel adjacent to the tapered door jamb is adapted to form a door case 11 which is formed integral with the body of the pressure vessel. A temperature control jacket 12 surrounds the body of the pressure vessel 1 which is provided with an expansion joint as at 13 and suitable pipe connections for the inlet and exhaust for the transmission of heating and cooling mediums thereto. As shown in Figs. 1, 2, 3, 4, 5, 6, 9, 10 and 11 the vertically extending left hand forward edge portion of the door case 11 is formed with a plurality of hinge lugs 14 between which the hinge lugs 15 of the door 8 are mounted each having registering openings 16 for receiving a hinge bolt 17. The vertically extending outer edge of the door case 11 has a plurality of spaced ears 18 between which the serrated swinging edge 19 of the door 8 is adapted to be latched. The spaced ears 18 have registering apertures 20 for receiving a locking bolt 21 which is journaled therein, and said locking bolt is formed with cut out segments between the spaced ears 18 as at 22. The serrated swinging edge 19 of the door 8 which is adapted to be latched is somewhat shorter than the thickness of the locking bolt 21 and is provided with an arc shaped recess as at 23 for engaging the locking bolt 21 when the door is in the locked position as indicated in Fig. 5, but will allow the door to be opened when the locking bolt 21 is rotated by the locking lever 24 to the position indicated in full lines in Fig. 4 to allow the projecting serrated swinging edge 19 of the door to pass through the cut out segment portion 22 of the locking bolt 21. A bail 25 is secured to opposite sides of the

3

door 8 and extends beyond one edge of the same and provided with a handle 26 by means of which the door may be swung open or closed manually when it is in the unlocked position and to reduce the weight of the door it may be provided with a circular recess 27.

The locking lever 24 is secured to the locking bolt 21 by means of a nut 28 and is further keyed thereto at 29 together with a washer 30 which is provided with stop projections 31 and 32 for engaging a stop pin 33 for limiting the rotation of the locking bolt 21. The other end of the locking bolt 21 has a tubular sleeve 34 keyed thereto as at 35 and is provided with a recess 36 for receiving a tooth 37 extending from the upper end of an interlocking release lever 38 which is pivoted as at 39 to a bracket 40 mounted on the end of a valve casing 41 adjacent to the tubular sleeve 34 by means of bolts 42. The interlocking release lever 38 is also provided at its inner end with a rocking arm 43 for engaging the upper end of the stem 44 of a valve 45 which is normally held on its valve seat 46 by means of a spring 47 which is retained in position by means of a threaded socket member 48 that can be removed for cleaning while the stem 44 is provided with a gland 49 to prevent leakage.

As indicated diagrammatically in Fig. 11 an air vent pipe 50 is connected to the threaded opening 3 in the closed end 2 of the pressure vessel and controlled by a valve 51. Threaded opening 4 is connected by a pipe 52 extending to a branch pipe 53 connected to a water pipe 54 controlled by a valve 55 and a high pressure steam pipe 56 controlled by a valve 57. Pipe 52 is also connected by means of a pipe 58 to a port 59 formed in the valve casing 41. The threaded opening 5 is connected to an exhaust pipe 60 controlled by a valve 61. Said exhaust pipe 60 has a bypass pipe connection 62 extending to a port 63 formed in the valve casing 41.

The operation of the device is as follows: Assuming that the door is locked and the parts are in the position in Figs. 1, 2, 3, 5, 6, 9, 10 and 11, the interlocking valve 45 is closed by pressure of the spring 47 beneath the valve and the vent pipe valve 51 is open and the high pressure valve 57 and the exhaust valve 61 are closed, valve 55 is then open until the pressure vessel is filled with water, valve 55 is then closed and high pressure valve 57 is opened and the vent pipe valve 51 closed and the vessel subjected to 3000 to 5000 lbs. per square inch pressure, which may be considerably more in large sized pressure vessels, to vulcanize the plastic material. During the vulcanizing operation the pressure in the vessel acts on the interlocking valve 45 keeping it closed tight and making it impossible to move the interlocking release lever 38. After the high pressure valve 57 has been closed and exhaust valve 61 opened and the pressure released the interlocking release lever 38 can be pulled towards the operator disengaging the tooth 37 from the recess 36 in the tubular sleeve 34 and making it possible to swing the locking lever 24 laterally into the unlocked position for unlocking the door 8. As the locking bolt 21 is rotated the tooth 37 will ride over the outer surface of the sleeve 34 and will be held in that position by the weighted end of the lever thereby holding the interlocking valve 45 open until the locking lever 24 is again swung into the locking position.

For all positions of the interlocking release lever 38 with the exception of the fully locked position the interlocking valve 45 is kept open.

4

Should the operator by mistake try to admit pressure to the vessel the interlocking valve 45 will bypass the water and high pressure and prevent pressure from building up in the vessel.

For the smaller sized pressure vessels the doors may be manually operated to swing vertically for opening or closing the door by means of the handle 26 of the bail 25 when the door is unlocked as disclosed in my copending application Serial No. 759,039.

In large sized pressure vessels as disclosed in this application where the pressure is considerably greater the doors may weigh as much as five or six thousands pounds and are obviously too heavy to lift manually; when this is the case it is desirable to hinge the door to swing horizontally and to provide an auxiliary means to help support the door during the opening and closing operations.

In these larger sized pressure vessels it is desirable to forge the door case 11 integral with the body of the pressure vessel 1 and surround the body of the pressure vessel with a jacket 12.

The hinge bolt 17 is disposed vertically and extends above the door case 11 as at 64, and is provided with a collar 65 integral therewith for engaging the top of the hinge lugs 14 of the door case 11. Upon the extending end 64 of the hinge bolt 17 is mounted a jib-crane comprising a cylindrical portion 66 mounted on the extending end 64 which is enlarged at its lower end as at 67 to receive a ball bearing 68 while upon the upper end 69 of 64 which is reduced slightly is mounted a roller bearing 70. The upper end of the cylindrical portion 66 is provided with a cap 71 which is secured thereto by means of bolts 72. The cylindrical portion 66 is provided with an extending arm 73 with a tubular outer end 74 for receiving a stud bolt 75, the upper end of which is threaded as at 76 to receive nuts 77 to act against the upper end of the tubular portion 74 while the lower end of said stud bolt 75 is threaded as at 78 and secured to the top central portion of the door 8; in this manner when the door is unlocked the operator by means of the bail handle 26 can easily swing the hinged door horizontally and the jib-crane will form an auxiliary support therefor.

Although I have shown and described my invention in considerable detail, I do not wish to be limited to the exact and specific details shown and described, but may use such substitutions, modifications or equivalents thereof, as are embraced within the scope of my invention or as pointed out in the claims.

I claim:

1. A pressure vessel comprising a tubular body portion having a pressure chamber open at one end, a door jamb formed within the open end portion of the vessel, a door case formed integral with the pressure vessel surrounding the open end portion of the vessel, a swinging door attached by a hinge to the door case adapted to engage the door jamb for closing said open end, said hinge for the door including a hinge bolt having an end portion projecting beyond an edge of the door, means for swinging the door to the open and closed positions, an arm formed with a cylindrical end portion mounted on the projecting end of the hinge bolt and extending outwardly therefrom and having a tubular outer end, a stud bolt connecting the tubular outer end portion of the extending arm and the central top portion of the door adapted to form an auxiliary support for the door during the opening and

closing operations, a locking bolt mounted on the door case for latching the swinging edge of the door in the closed position, means for rocking the locking bolt to latch and unlatch the door, and means for holding the bolt against rotation when the door is closed.

2. A pressure vessel comprising a tubular body portion having a pressure chamber open at one end, a door jamb formed within the open end portion of the vessel, a door case extending around the open end portion of the vessel, a swinging door attached by a hinge to the door case adapted to engage the door jamb for closing said open end, means for swinging the door to the open and closed positions, said hinge for the door including a hinge bolt having an end portion extending beyond an edge of the door, a jib-crane mounted on the extending portion of the hinge bolt and having an extending arm, a stud bolt connecting the outer end of the extending arm and the central top portion of the door adapted to form an auxiliary support for the door during the opening and closing operations, a locking bolt mounted on the door case for latching the swinging edge of the door in the closed position, means for rocking the locking bolt to latch and unlatch the door, and means for holding the locking bolt against rotation when the door is closed.

3. A pressure vessel comprising a tubular body portion having a pressure chamber open at one end, a door jamb having a beveled surface formed within the open end portion of the vessel, a door case extending around the door jamb formed integral with the vessel, a swinging door attached by a hinge to the door case having a frusto-conical valve surface adapted to engage the beveled surface of the door jamb for closing said open end, means for swinging the door to the open and closed positions, said hinge for the door including a hinge bolt having an end portion extending beyond an edge of the door, a jib-crane mounted on the extending end portion of the hinge bolt and having an extending arm, a bolt connecting the outer end of the arm with the top central portion of the door adapted to form an auxiliary support for the door during the opening and closing operations, a locking bolt mounted on the door case for latching the swinging edge of the door in the closed position, means for rocking the locking bolt to latch and unlatch the door, and means for holding the locking bolt against rotation when the door is closed.

4. In a pressure vessel, a tubular body portion having a pressure chamber open at one end, a door jamb formed at the open end portion of the vessel, a door case adjacent to the open end portion of the vessel, a swinging door attached by a hinge to the door case adapted to engage the door jamb for closing said open end, means for swinging the door to the open and closed positions, said hinge for the door including a hinge bolt having an end portion extending beyond an edge of the door, a collar on the extending portion of the hinge bolt or engaging the end of the hinge, a jib-crane comprising a cylindrical portion mounted on the extending end of the hinge bolt and supported on the collar and having an arm with a tubular outer end portion, a stud bolt connecting the tubular outer end portion of the arm with the central portion of the top of the door, said jib-crane adapted to form an auxiliary support for the door during the opening and closing operations, a locking bolt mounted on the door case for latching the swinging edge of the door in the closed position, means

for rocking the locking bolt to open and close the door, and means for holding the locking bolt against rotation when the door is closed.

5. In a pressure vessel, a tubular body portion having a pressure chamber open at one end, a door jamb formed at the open end portion of the vessel, a door case adjacent to the open end portion of the vessel, a swinging door attached by a hinge to the door case adapted to engage the door jamb for closing said open end, means for swinging the door to the open and closed positions, said hinge for the door including a hinge bolt having an end portion extending beyond an edge of the door, a collar on the extending portion of the hinge bolt for engaging the end of the hinge, a jib-crane comprising a cylindrical portion provided with an anti-friction bearing therein at each end mounted on the extending end of the hinge bolt and supported on the collar, said cylindrical portion of the jib-crane having an arm with a tubular outer end portion, a stud bolt connecting the tubular outer end portion of the arm with the central portion of the door, said jib-crane adapted to form an auxiliary support for the door during the opening and closing operations, a locking bolt mounted on the door case for latching the swinging edge of the door in the closed position, and means for holding the locking bolt against rotation when the door is closed.

6. In a pressure vessel, a tubular body portion having a pressure chamber open at one end, a door jamb formed at the open end portion of the vessel, a door case adjacent to the open end portion of the vessel, a swinging door attached by a hinge to the door case adapted to engage the door jamb for closing said open end, means for swinging the door to the open and closed positions, and a jib-crane having one end pivotally mounted on the door case and the other end connected to the top central portion of the door adapted to form an auxiliary support for the door during the opening and closing operations.

7. A pressure vessel comprising a tubular body portion having a pressure chamber open at one end and closed at the opposite end, a door jamb formed within the open end portion of the vessel, a door case formed integral with the tubular body portion of the pressure vessel surrounding the open end portion of the pressure chamber, a door attached by a hinge to the door case, means for swinging the door to the open and closed positions to disengage and engage the door jamb, an auxiliary support for the door during the opening and closing operations, means for automatically locking the swinging edge of the door when the door is closed, inlet and exhaust pipe connections having valves for controlling the supply of fluid pressure to and from the pressure chamber, an interlocking valve having pipe connections to the fluid pressure supply and exhaust pipe connections for the pressure chamber, resilient means for normally holding the interlocking valve seated at all times when the door is closed, an interlocking release lever, means actuated by the locking means for the swinging edge of the door engaging the interlocking release lever for holding the interlocking valve open at all times to bypass the fluid pressure for the pressure chamber to the exhaust pipe connection when the door is open.

8. A pressure vessel comprising a tubular body portion having a pressure chamber open at one end and closed at the opposite end, means for controlling the supply of fluid pressure to and from the chamber, a door jamb formed within the open end portion of the tubular body, a door

case surrounding the open end portion of the chamber, a door attached by a hinge to the door case, said hinge for the door having an end portion extending beyond an edge of the door, a jib-crane mounted on the extending portion of the hinge bolt and having an extending arm, a stud bolt connecting the outer end of the arm and the central top portion of the door adapted to form an auxiliary support for the door during the opening and closing operations, means for swinging the door to the open and closed positions, a bolt mounted on the door case adapted to be rotated to lock and unlock the door, means for holding the bolt when the door is locked to prevent rotation, and means adapted to by-pass the fluid pressure for the pressure chamber to an exhaust connection when the door is unlocked.

9. A pressure vessel comprising a tubular body portion having a pressure chamber open at one end and closed at the opposite end having threaded openings for pipe connections with means for controlling the fluid pressure to and from the chamber, a door jamb formed within the open end portion of the vessel, a door case surrounding the open end portion of the vessel, a door attached by a hinge to the door case, said hinge for the door including a hinge bolt having an end portion extending beyond an edge of the door, a jib-crane mounted on the extending end portion of the hinge bolt and having an extending arm, a bolt connecting the outer end of the arm with the top central portion of the door adapted to form an auxiliary support for the door during the opening and closing operations, means for swinging the door to the open and closed positions to engage and disengage the door jamb, spaced ears extending from the door case, a bolt mounted for rocking movement in the ears for latching the door in the closed position, means for rocking the bolt to open and close the door, and means for limiting the rocking movement of the bolt.

10. A pressure vessel comprising a tubular body portion having a pressure chamber open at one end and closed at the opposite end, threaded openings in the closed end for pipe connections with means for controlling the fluid pressure to and from the chamber, a door jamb having a beveled surface formed within the open end portion of the tubular body, a door case surrounding the open end portion of the chamber, a door attached by a hinge to the door case having an extending frusto-conical valve surface adapted to engage the beveled surface of the door jamb for closing said open end, said hinge for the door including a hinge bolt having an end portion extending beyond an edge of the door, a collar on the extending portion of the hinge bolt for engaging the end of the hinge, a jib-crane comprising a cylindrical portion mounted on the extending end of the hinge bolt and supported on the collar and having an arm with a tubular end portion, a stud bolt connecting the tubular end portion of the arm with the central top portion of the door, said jib-crane adapted to form an auxiliary support for the door during the opening and closing operations, means for swinging the door to the open and closed positions, a bolt mounted on the door case adapted to be rotated to latch, and unlatch the door, means for holding the bolt when the door is locked to prevent rotation, and means adapted to bypass the fluid pressure for the pressure chamber to an exhaust connection when the door is unlocked.

11. A pressure vessel comprising a tubular body portion having a pressure chamber open

at one end and closed at the opposite end, inlet and outlet pipe connections to the closed end of the vessel having valves for controlling the supply of fluid pressure to and from the chamber, a door jamb formed within the open end portion of the tubular body, a door case surrounding the open end portion of the chamber having a forward edge, a door hinged to the forward edge of the door case having a serrated swinging edge said hinge for the door including a hinge bolt having an end portion extending beyond an edge of the door, a jib-crane mounted on the extending portion of the hinge bolt and having an extending arm, a stud bolt connecting the outer end of the arm and the central top portion of the door adapted to form an auxiliary support for the door during the opening and closing operations, means for swinging the door to the open and closed positions, a plurality of spaced ears extending from the forward edge of the door case adjacent to the swinging serrated edge of the door when closed, registering apertures formed in the ears, arc-shaped recesses formed in the serrated swinging edge of the door, a locking bolt mounted for rocking movement in the apertures in the ears and the arc-shaped recesses formed in the swinging edge of the door having cut out segments between the spaced ears adapted to latch and unlatch the swinging edge of the door, means to prevent rocking movement of the bolt when the door is latched, and means adapted to bypass the fluid pressure for the pressure chamber to an exhaust connection when the door is unlocked.

12. A pressure vessel comprising a tubular body portion having a pressure chamber open at one end and closed at the opposite end, a door jamb formed with the open end portion of the vessel, a door case surrounding the open end portion of the vessel, a door hinged to the door case, said hinge for the door including a hinge bolt having an end portion extending beyond an edge of the door, a jib-crane mounted on the extending portion of the hinge bolt and having an extending arm, a stud bolt connecting the outer end of the arm and the central top portion of the door adapted to form an auxiliary support for the door during the opening and closing operations, means for swinging the door to the open and closed positions to disengage and engage the door jamb, means for locking the swinging edge of the door when the door is closed, inlet and outlet pipe connections to the closed end of the vessel having valves for controlling the supply of fluid pressure to and from the chamber, a valve having a pipe connection to the fluid pressure supply pipe to the pressure chamber, resilient means for normally holding the valve seated when the door is closed and the fluid pressure to the vessel is cut off, fluid pressure means from the supply pipe for retaining the valve closed when the fluid pressure is admitted into the chamber of the vessel when the door is closed, and means for opening the valve to bypass the fluid pressure for the pressure chamber to an exhaust connection when the door is unlocked.

13. A pressure vessel comprising a container having a pressure chamber open at one end and closed at the opposite end, a door surrounding the open end portion of the vessel, inlet and exhaust pipe connections to the pressure chamber having valves for controlling the fluid pressure to and from the pressure chamber, a swing-

ing door hinged to the door case for closing the open end of the pressure chamber, said hinge for the door including a hinged bolt having an end portion extending beyond an edge of the door, a collar on the extending portion of the hinge bolt for engaging the end of the hinge, a jib-crane comprising a cylindrical portion provided with an anti-friction bearing therein at each end mounted on the extending end of the hinge bolt and supported on the collar, said cylindrical portion of the jib-crane having an arm with a tubular outer end portion, a stud bolt connecting the tubular outer end portion of the arm with the central top portion of the door, said jib-crane adapted to form an auxiliary support for the door during the opening and closing operations, means for swinging the door to the open and closed positions, means for automatically locking the door in the closed position, an interlocking valve having pipe connections to the fluid supply and exhaust pipes for the pressure chamber, resilient means for normally holding the valve seated when the door is closed, and means for opening the valve when the door is opened.

14. A pressure vessel comprising a tubular body portion having a pressure chamber open at one end and closed at the opposite end, a door jamb formed within the open end portion of the vessel, a door case surrounding the open end portion of the vessel, a door hinged to the door case, said hinge for the door including a hinge bolt having an end portion extending beyond an edge of the door, a collar on the ex-

tending portion of the hinge bolt for engaging the end of the hinge, a jib-crane comprising a cylindrical portion mounted on the extending end of the hinge bolt and supported on the collar and having an arm with a tubular end portion, a stud bolt connecting the tubular end portion of the arm with the central portion of the top of the door, said jib-crane adapted to form an auxiliary support for the door during the opening and closing operations, means for swinging the door to the open and closed positions to disengage and engage the door jamb, means for automatically locking the swinging edge of the door when the door is closed, inlet and exhaust pipe connections having valves for controlling the supply of fluid pressure to and from the pressure chamber, an interlocking valve having pipe connections to the fluid pressure supply and exhaust pipe connections for the pressure chamber, resilient means for holding the valve seated at all times when the door is closed, and means for holding the valve open at all times when the door is open.
